UNITED STATES PATENT OFFICE.

FRANCIS J. CANCIANICH, OF NEWPORT NEWS, VIRGINIA.

HAT-FASTENER.

1,341,356.

Specification of Letters Patent. Patented May 25, 1920.

Application filed September 11, 1919. Serial No. 323,046.

To all whom it may concern:

Be it known that I, FRANCIS J. CANCIANICH, a subject of the King of Italy, residing at Newport News, in the county of Warwick and State of Virginia, have invented

5 certain new and useful Improvements in Hat-Fasteners; and I do hereby declare the following to be a full, clear, and exact description of the invention, such as will enable others skilled in the art to which it

10 pertains to make and use the same.

My invention relates to hat fasteners, the principal object being to provide a fastener adapted to be used in securing a woman's

15 hat in position upon the head to take the place of the ordinary pin commonly used.

Another important object of my invention is to provide a hat fastener which will obviate the danger of injury to the head

20 as is ordinarily experienced with the usual hat pin.

A further object of the invention is to provide a hat fastener to be used in conjunction with women's hats, which when engaged with the hair will positively retain the hat in proper position on the head and which at the same time will not perforate or otherwise injure the hat.

A still further object of the invention is to

30 provide a woman's hat fastening which will permit the hat to be engaged upon the wearer's head without the use of a mirror and will always engage the hair at the proper point to retain the hat in its proper

35 position.

Another object of the invention is to provide a fastener for women's hats which may be readily attached to the hat and used in conjunction with hats of various types, the

40 construction being such as to cause the wearer no inconvenience and to be comfortable to the head.

An additional object of the invention is to provide a hat fastening device having

45 the above characteristics, which is simple in construction, which consists of few parts, and which may be manufactured and sold at a minimum cost.

With the above and other objects and advantages in mind, the invention consists in the novel combination of elements, construction and arrangement, operation and specific features all of which are hereinafter enlarged upon and explicitly defined in the

55 subjoined claims.

On the drawings Figure 1 is a bottom plan view of my improved hat fastening in position in a hat, parts of the hat being broken away;

Fig. 2 is a top plan view of the device detached from the hat;

Fig. 3 is an enlarged sectional view taken on line 3—3 of Fig. 2, and

Fig. 4 is an enlarged detail view illustrating the mounting of the hair engaging tines, and

Fig. 5 is a detail view of one of the parts used in conjunction with the invention.

Referring to the drawings in detail wherein like characters of reference designate like parts in all the views the numeral 5 designates a plate which in this instance is frusto-conical in shape and is cut out at opposite sides as indicated at 6 to render the plate light and to receive the wearer's hair.

70 In order to further reduce the weight of the plate 5 and to allow the interior of the hat to be ventilated, the plate is provided with perforations 7. It will be stated that owing to the constant change in the shape of

80 hats the plate 5 will be of such shape as to conform to the contour of the interior of the hat. Securing flanges 8 are formed at the radial edges of the plate 5 and are provided with openings 9 for the reception of

85 stitching whereby the plate is secured in the crown of the hat. The circumferential edge of the plate 5 is also provided with openings 9' for the reception of stitching. As illustrated in Fig. 1 the plate is positioned

90 in the crown of the hat and overlying this plate is a piece of fabric 10 to which the flanges 8 and the plate 5 are stitched as indicated at 11.

95 Formed upon the central part or the flat surface of the plate 5 is an upstanding semicircular member 12. Rotatably mounted on this flat surface and about the member 12 as an axis is an elongated plate 13. Extending from opposite ends of the rotatable plate 13 is a pair of oppositely disposed tines or hair engaging pins 14, each of which includes a length of wire bent adjacent its inner end as at 15 and extended obliquely to lie upon the outer face of the plate 5.

100 105 Each of the lengths of wire are bent reversely as indicated at 17 and longitudinally curved. The longitudinally curved parts of each of the tines is slidably engaged in guides 19 disposed at the radial

110

edges of the plate 5. The plate 5 is further provided with slots 20 which open at the radial edges and secured to the other face of the plate and underlying the slots are housings 21 to protect the points of the tines 14 when in retracted position.

A stationary plate 22 is disposed above the rotatable plate 13 in spaced relation thereto and is secured to the plate 5 by 10 downturned clips 23 passing through the plate and bent at right angles thereto. Extending downwardly from the plate 22 is a pin 24 formed with a head 25 at its lower end and embracing this pin and head is a 15 helical spring 26, one end of which is secured to an ear 27 struck in the plate 22 and its opposite end secured to an ear 28 carried by the plate 13. Normally the spring 26 urges the plate 13 to a position where the tines 14 20 will project beyond the housings as illustrated in Figs. 1 and 2 to engage the wearer's hair.

In order to retract the tines there is provided an operating chain or other flexible 25 element 29 which passes through the hat as illustrated at 30 and is attached to one of the tines 14. Depending from this chain 29 is a grasping member 31. This chain is movable in a guide 32 disposed upon one of the 30 radial edges of the plate 5 and disposed at a point where it will not obstruct the tine having the chain attached thereto during the retracting operation. A keeper 33 is disposed on the plate 5 adjacent the guide 32 35 and is contracted at one side to receive a latching element 34 disposed intermediate the ends of the chain to retain the tines in retracted position.

From the above disclosure it will be apparent 40 that after the hat is placed upon the wearer's head it is only necessary to disengage the latching element from the keeper 33 to allow the tines to be engaged with the wearer's hair which will positively retain 45 the hat in position on the head.

The construction illustrated and described is a practical embodiment of the invention, but it will be understood that the same may be modified in many respects, and my limits 50 of such modification are only governed by the subjoined claims.

What I claim is:

1. A hat fastening including a plate cut out at opposite sides thereof, a plurality of 55 hair engaging tines having their inner ends connected together and pivoted upon the plate, a spring operatively connecting the tines and normally urging the same to a position to bridge the cut out parts of the plate, and means for retracting the tines and locking the same in retracted position.

2. A hat fastening comprising a plate to be mounted in a hat, oppositely disposed hair engaging tines having their inner ends 60 fixed to a common point and rotatable about

a common axis, a spring normally urging the tines into engagement with the wearer's hair, a flexible element having one end attached to one of the tines, a guide on the plate through which the flexible element 70 passes, and a keeper on the plate adapted to engage the flexible element to retain the tines in retracted position.

3. The combination with a hat, of a perforated plate of a shape to conform to the 75 interior of the hat, the plate being cut out at diametrically opposite points, securing flanges formed at the radial edges of the plate and provided with openings to receive securing means, a plate rotatable upon the 80 upper face of the perforated plate, oppositely disposed hair engaging tines carried thereby, a coil spring normally urging the plate to a position to cause the tines to engage the hair, and a flexible element passing 85 through the hat having one end attached to the tines whereby the same may be retracted.

4. In a hat fastening, a plate adapted to be secured within a hat, a plate rotatable 90 on the first mentioned plate, oppositely disposed tines carried thereby, a stationary plate disposed above the rotatable plate and spaced therefrom and fixed to the first mentioned plate, a stem projecting from the latter plate, a helical spring encircling the stem having one end engaged with the said plate and its opposite ends fixed to the rotatable plate, the spring normally urging the plate to a position to engage the tines with 95 the hair, a flexible element operatively connected with the tines for retracting the latter, and means for engaging the flexible element to retain the tines in retracted position.

5. In a hat fastening, a concavo-convex plate to be secured within a hat, and provided with relatively large openings at diametrically opposite points to accommodate the wearer's hair, and a plurality of tines 100 fixed to a common point and rotatable on the plate and adapted to bridge the openings to engage the hair.

6. In a hat fastening, a concavo-convex plate adapted to be secured within a hat, a 115 plurality of tines at its inner ends connected to a common point, said tines being bent adjacent their inner ends to dispose the major portion thereof in a plane to lie against the plate, and means for projecting the tines 120 for engagement with the wearer's hair and to disengage the same therefrom.

7. In a hat fastening, a substantially concavo-convex plate provided with a central flat portion, an elongated member rotatable 125 on the latter, a plurality of hair engaging tines carried by the elongated member, a stationary plate overlying the elongated member and connected to the flat portion, a head depending from the stationary plate, and a 130

coil spring engaging the head and having one end connected with the elongated plate normally engaging the tines with the hair.

8. In a hat fastening, a plate adapted to 5 be mounted within a hat, an upstanding semicircular member carried by the plate, an elongated member provided with a central opening receiving the semi-circular member, and a coil spring disposed within the semi- 10 circular member and having one end operatively connected with the plate and its oppo-

site end connected with the elongated member to rotate the same in one direction, and hair engaging means carried by the elongated member.

15

In testimony whereof I affix my signature in presence of two witnesses.

FRANCIS J. CANCIANICH.
